CONTACT CONSTRUCTION WITH METALLIC CONTACT MEMBERS AND AUXILIARY METALLIC ARC SUPPRESSANT CONDUCTING MEMBERS

Joseph J. Gribble, Fox Point, Wis., assignor to Square D Company, Park Ridge, Ill., a corporation of Michigan

Filed May 9, 1960, Ser. No. 27,702

7 Claims. (Cl. 200—166)

This invention relates to an electrical contact device and more particularly to an electrical contact device employing special contacts in a relation which provides a more effective self-contained, arc-extinguishing means.

One of the most persistent problems encountered in the use of electrical contacts is the excessive and premature pitting and erosion of such contacts by the arcing which occurs between the contacts as a circuit is made or broken. Because of this arcing, the contacts must be replaced frequently, thereby involving considerable expense in time and materials.

It is an object of the present invention to provide electrical contacts which are much less subject to pitting, burning and erosion by arcing and which have a substantially longer life than that of prior contacts.

A further object of the invention is to provide electrical contacts that extinguish the arc and resist welding more efficiently than that of prior constructions.

A further object of the invention is to provide an electrical contact construction which is economical to manufacture and that is efficient and trouble-free in use, and in which the specific contacts are arranged in a relation to the arc path so that the arc is moved efficiently to the extinguishing position.

Briefly, the foregoing objects are accomplished by the provision of an electrical contact construction including a pair of opposed coating contacts, each of said contacts having a contiguous auxiliary arc receiving conductor, and each main contact and its auxiliary conductor being mounted, respectively, adjacent the outer free, parallel-spaced end portions of an electrical conducting bar. The contacts are oppositely spaced in face to face relation and are adapted for movement into and out of contact with each other for making and breaking an electrical circuit. The auxiliary conductors are disposed also in spaced, face to face relation, but do not come into contact with each other when the contacts are in either open or closed position. More specifically, each contact and its contiguous auxiliary conductor present a stepped construction, in side elevational view, with the distance between the contacts being less than the distance between the contiguous auxiliary conductors.

In operation, with the contacts in engagement with each other, electric load current flows in through one of the conducting bars, through the engaged contacts and thence through the other conductor bar. This current creates a magnetic field having a resultant force directed outwardly towards the free ends of the conducting bars. Upon opening of the contacts, if an arc is created, it acts as a path for the current so that the magnetic field is maintained. When the contacts are parted to break the electric circuit and an arc is created between such contacts, the arc is driven by the magnetic field normally in a predetermined direction from the contacts. In accordance with this invention, the auxiliary conductors are arranged so that the normal path of the arc is directly between their faces and the space outwardly from the conductors in the direction of arc travel is unobstructed.

Furthermore, contacts are formed of a refractory composition such as tungsten carbide impregnated with silver, such material being hard and of high strength and particu-

larly resistant to welding because of its high melting point. The auxiliary conductors are formed of a semi-refractory composition such as silver cadmium oxide, which is an arc-suppressant material of high interrupting capacity. Thus, the magnetic field created by the current flowing through the contacts causes the arc to travel from the partially spaced weld-resistant contacts to the substantially spaced arc-suppressant, auxiliary conductors where the arc is interrupted. With this construction, an electrical contact device is provided having self-contained arc extinguishing means, such contact device being of unusually simple construction and having a substantially longer life than that of prior constructions.

Other objects and advantages of the invention will become apparent from the following description taken in conjunction with the drawings, wherein:

FIG. 1 is a perspective view of an electrical contact device constructed in accordance with the invention, with the contacts in open position;

FIG. 2 is a top plan view of the lower contact member shown in FIG. 1;

FIG. 3 is a side elevational sectional view taken along the line 3—3 of FIG. 2; and

FIG. 4 is a side elevational view of the electrical contact device shown in FIG. 1, the device being shown in closed position.

Referring to the drawings, there is shown an electrical contact device A of the invention and comprising the contact supporting means in the form of two spaced electrical load current conducting bars 10 and 12 having parallel outer end portions, the outer end portions having coating, oppositely disposed, contacts or contact members 14 and 16, respectively, supported fixedly thereon in face to face relation. The contact 14 has a contiguous auxiliary conductor 18 and the contact 16 has a contiguous auxiliary conductor 20.

The conducting bars 10 and 12 are adapted for movement toward and away from each other in any well known manner, whereby the contacts 14 and 16 move into and out of engagement with each other for making and breaking an electric circuit. For illustration, the bar 12 is shown as stationary and the bar 10 is movable about a pivot 13 toward and away from the bar 12.

The auxiliary conductors 18 and 20 are disposed in spaced, face to face relation a greater distance apart than the contacts 14 and 16 so that they do not come into contact with each other even when the contacts 14 and 16 are in closed position. Thus the contacts and conductors present a stepped construction.

In operation, with the contact members 14 and 16 in engagement with each other, as shown in FIG. 4, electric current flows, for example, through the conducting bar 10, down through the engaged contacts 14 and 16, and thence through the conducting bar 12, as shown by the arrows 17. This current flow creates a magnetic field having a resultant force which is directed outwardly, to the right in FIG. 4, toward the free ends of the bars 10 and 12, as indicated by the arrow 21. When the contacts 14 and 16 are parted, as shown in FIG. 1, an arc is formed between the contacts and the magnetic field causes the arc to travel from the contacts to the auxiliary conductors 18 and 20 where the arc is broken, such arc progression being represented by the broken lines 22. Thus the conductors 18 and 20 are arranged in parallel spaced relation along the normal path of the arc. This path is in a direction to the right in FIG. 4, and is unobstructed for a distance outwardly beyond the conductors 18 and 20 sufficient to permit interruption of the arc.

The contacts 14 and 16 are formed of a refractory composition, such as a matrix of tungsten carbide impregnated with silver. This composition is hard and of high strength and resistant to arc erosion and wear, yet is a

good conductor of electricity. In the preferred form, such composition consists of about 50% tungsten carbide and about 50% silver, both by volume. However, these percentages may be varied somewhat. For example, tungsten carbide may be from about 40% to 60%, and the silver may provide the balance.

The contiguous auxiliary conductors are formed of a semi-refractory material, such as silver cadmium oxide. This composition is highly arc-suppressant and has a high interrupting capacity. In the preferred form, such composition consists of about 85% silver and about 15% cadmium oxide, both by volume. The percentages may be varied. For example, the silver may range from about 80% to 90% and the cadmium oxide may provide the balance.

Having thus described my invention, I claim:

1. A contact construction comprising a pair of elongated load current conducting bars extending lengthwise alongside each other in face to face spaced relation from each other transversely of their lengths and movable transversely of their length toward and away from each other so that the load current path therein is endwise of the bars, metallic contact members on the adjacent faces of the bars, respectively, near to, but spaced from, one end of the pair, and supported by the bars in spaced face to face relation, and movable by the bars into contact with each other upon movement of the bars transversely of their length toward each other, whereby, upon establishment of an arc between the members when they are moved apart, a magnetic field is established by the load current which forces the arc to travel from between the contact members endwise of the bars towards and beyond said one end of the pair of bars, auxiliary conducting members of highly arc suppressant metallic material mounted on the bars, respectively, outwardly from the contact members toward said one end of the pair and arranged so that they extend directly from the adjacent outer ends of the contact members, respectively, outwardly toward said end of the pair of bars, and are in spaced face to face relation to each other in the direction of separation of the contact members in all positions of the contact members, means supporting the bars so that the direct path of travel of the arc from between the contact

members under the influence of the magnetic field created by the load current, outwardly endwise of the bars past said one end of the pair, is unobstructed, endwise of the bars, outwardly from the contact members, past said auxiliary members and therebeyond a distance sufficient to permit interruption of the arc while it is substantially unconstrained endwise and laterally of the bars, said metallic contact members being of material of high electrical conductivity and high resistance to welding, wear, and arc erosion, and said auxiliary conducting members being of metallic material of high arc interrupting capacity.

2. The structure according to claim 1 wherein said contact portion is formed of tungsten carbide impregnated with silver.

15 3. The structure according to claim 2 wherein said tungsten carbide is present in an amount of about 50% and silver is present in an amount of about 50%, by volume.

20 4. The structure according to claim 1 wherein said auxiliary portion is formed of silver cadmium oxide composition.

25 5. The structure according to claim 4 wherein said silver is present in an amount of about 85% and the cadmium oxide is present in an amount of about 15%, by volume.

30 6. The structure according to claim 1 wherein said contact portion is formed of a material consisting of about 50% tungsten carbide and about 50% silver, and said auxiliary portion is formed of a material consisting of about 85% silver and about 15% cadmium oxide, by volume.

35 7. The structure according to claim 1 wherein said contact members are formed of a material consisting of about 40% to 60% tungsten carbide and from about 60% to 40% silver, both by volume, and said auxiliary members are formed of a material consisting of about 80% to 90% silver and from about 20% to 10% cadmium oxide, both by volume.
